COOKING STOVE

Arthur L. Williams, Maywood, and Arthur J. Langlois, Huntington Park, Calif.; said Langlois assignor to said Williams

Application September 17, 1937, Serial No. 164,344

2 Claims. (Cl. 126—42)

This invention relates to cooking stoves and relates more particularly to cooking stoves of the cabinet type. A general object of this invention is to provide a cooking stove of the character mentioned embodying novel and practical safety control means.

Cooking stoves of the cabinet type embody covers for covering and concealing the top burners and adjacent parts when the said burners are not in use. The top burners of a stove of the character referred to are individually controlled by manual valves at the front of the stove and are usually ignited by a pilot burner that remains lit at all times. Quite frequently the cover for the top burners is lowered to its closed position when one or more of the burners are ignited with the result that the cover is seriously injured or destroyed by the heat from the burners. Further, a top burner valve may be inadvertently opened or may be opened by a child when the cover is closed, resulting in igniting of the burner and the accompanying injury to the cover, or resulting in the escape of unburned gas under the close cover and a possible explosion.

Another object of this invention is to provide an automatic control for the top burners of a cabinet type cooking stove that prevents igniting of the top burners when the cover is closed and that automatically extinguishes the top burners when the cover is moved to the closed position.

Another object of this invention is to provide a cooking stove of the character mentioned embodying a valve for controlling the pipe which supplies the top burners and a control for the valve operated by movement of the cover whereby the supply of gas to the burners is cut off when the cover is closed.

Another object of this invention is to provide a cooking stove of the character mentioned in which the control for governing the valve of the supply pipe for the top burners is positive, operating to close the valve when the cover is moved to its closed position and operating to automatically open the valve when the cover is raised to its open position.

Another object of this invention is to provide a cooking stove of the character mentioned in which the control means for the top burners does not in any way affect the pilot burner for the top burners, or affect any of the other burners of the range.

A further object of this invention is to provide a control of the character mentioned for the top burners of a cabinet type cooking stove that is simple and inexpensive to embody in a stove at

the time of manufacture and that may be readily embodied in a previously constructed stove as an attachment.

The various objects and features of our invention will be fully understood from the following detailed description of a typical preferred form and application of the invention, throughout which description reference is made to the accompanying drawing, in which:

Fig. 1 is a fragmentary perspective view of a cooking range or stove embodying the control of the present invention showing the cover for the top burners in the raised position. Fig. 2 is an enlarged fragmentary end view of the stove showing the cover in the raised position and with a portion broken away to illustrate the control mechanism. Fig. 3 is an enlarged fragmentary plan view of the stove with a portion of the grill or plate broken away to illustrate the control means. Fig. 4 is an enlarged side elevation of the stove showing the cover in the closed position with a portion of the stove side broken away to illustrate the control mechanism, and Fig. 5 is an enlarged fragmentary vertical sectional view illustrating the connection between the cover and the link.

The present invention may be embodied in stoves of various makes and constructions and may be in the form of an attachment for previously constructed stoves. In the following detailed description we will describe a simple, preferred form of the invention applied to or embodied in a typical gas range of the cabinet type, it being understood that the invention is not to be construed as limited or restricted to the specific form or application of the invention about to be described, but is to be taken as including any features that may fall within the scope of the claims.

The portion of the typical range or stove illustrated in the drawing includes a rectangular body 10 having an oven compartment 11, a top burner grill or plate 12, a front panel 13, drawers 14 and a rear guard rail 15 projecting upwardly along its upper rear edge. A cover 16 is hinged to the range body 10 to be movable between the open position illustrated in Figs. 1, 2 and 3 of the drawing and the closed position illustrated in Fig. 4 of the drawing. The cover 16 is provided to cover and conceal the grill or plate 12 and the top burners and may be hinged to the range body 10 along its rear edge in the usual manner. Lugs 17 project rearwardly from the rear edge portion of the cover 16 and springs 18 are con-

nected with the lugs 17 to counterbalance the cover 16 and render it easy to move.

The particular range or stove illustrated in the drawing has four spaced top burners 19 positioned below openings 20 in the grill or plate 12. Suitable manifolds or branch pipes 21 extend from the burners 19 forwardly to a transverse header pipe 22 immediately behind the front panel 13. Valves 23 individually control the admission of the gas to the branch pipes 21 of the burners 19. The present invention is not primarily concerned with the details of the burner control valves 23 and such details are omitted from the present disclosure. The valves 23 have suitable knobs or handles accessible at the front panel 13. An oven control valve 24 is provided at the front panel 13 to govern the passage of gas through a pipe 25 which extends to the burner (not shown) of the oven 11. Flash tubes 26 radiate outwardly from a pilot burner 27 to the spaced top burners 19 and are operable to conduct gas from the burners 19 to the pilot burner 27 and to conduct the resultant flames back to the top burners 19 to ignite the same. In accordance with the invention a pipe 28 connects the pilot burner 27 with the oven supply pipe 25 whereby the burner 27 receives its gas from the pipe 25. A pipe 29 joins the pipe 28 and extends to the oven 11 of the stove to supply the pilot burner (not shown) of the oven with gas. The pilot burner pipes 28 and 29 are connected with the oven supply pipe 25 at points at the upstream side of the oven control valve 24 so that they are not controlled by the control valve 24. The header pipe 22 and the oven supply pipe 25 receive their supplies of gas in the manner to be hereinafter described.

The stove control or burner control of the present invention includes, generally, a line or pipe 30 for conducting gas to the header pipe 22 of the top burners 19. A main supply pipe 31 furnishing gas to the oven supply pipe 25 and the pipe 30, a valve 32 controlling the pipe 30 and an operative connection 33 between the cover 16 and the valve 32 whereby opening of the cover 16 opens the valve 32 and closing of the cover 16 closes the valve 32.

The pipe 30 for carrying gas to the header pipe 22 of the top burners 19 may be positioned differently in different stove constructions. In the particular case illustrated in the drawing the pipe 30 is arranged below the grill or plate 12 and extends rearwardly from one end of the pipe 22 in adjacent parallel relation to an end 34 of the stove body 10. The pipe 30 may be connected with the header pipe 22 by a suitable L 35. The main supply pipe 31 extends from the gas supply pipe or service line (not shown) to the range or stove. In accordance with the usual practice the pipe 31 extends upwardly at the rear of the stove body 10 and passes forwardly through an opening in the rear wall 38 of the stove body 10. A suitable T-fitting 37 connects the supply pipe 31 with the oven supply pipe 25 and the pipe 30. It is to be noted that the oven supply pipe 25 is connected with the main supply pipe 31 independently of the pipe 30 so that the control of the pipe 30 by the valve 32 does not affect the pilot burner 27 or the burners of the oven.

The valve 32 is the safety control valve of the invention and is provided to govern the pipe 30 which supplies gas to the top burners 19. The valve 32 is connected or interposed in the pipe 30 adjacent the T-fitting 37. The valve 32 is in the

nature of a plug valve or stop cock and embodies a projecting turnable stem 38. An operating lever 39 is fixed to the valve stem 38. The connection between the lever 39 and the valve stem 38 is preferably such that the lever may be set in various rotative positions with respect to the stem 38 and the plug of the valve 32. In the arrangement of parts illustrated in the drawing the valve 32 is positioned with its stem 38 projecting laterally or horizontally toward the adjacent side or end 34 of the stove body 10. The valve 32 is preferably such that turning of the lever 39 through an arc of substantially 90° effects opening or closing of the valve, depending upon the direction of turning of the lever.

The operative connection 33 between the valve 32 and the cover 16 is a positive automatic control for the valve whereby lifting of the cover 16 from its closed position to its open position opens the valve 32 and lowering of the cover 16 from its vertical open position to its closed position closes the valve 32. The operative connection 33 includes a part connected with and movable by the cover 16. In the preferred construction illustrated in the drawing this part is in the nature of a link 40 pivotally connected with the cover 16. A clip or lug 41 is secured to the cover 16 adjacent one edge to be in substantially the same vertical plane as the lever 39 of the valve 32. The lug 41 may be secured to the cover 16 by bolts or by welding 42, as illustrated. It is to be understood that if the control of the present invention is to be applied to a previously constructed stove the lug 41 may be secured to the cover 16 in other manners. The lug 41 has an opening and the link 40 has a finger 43 turnably received in the opening whereby the link is pivotally connected with the cover 16. The link 40 extends downwardly from the lug 41 and passes through a slot 44 in the grill or plate 12. The slot 44 is of sufficient length to freely receive the link 40 throughout the movement of the cover 16 and may receive the lug 41 when the cover is in its closed or horizontal position.

The control or operative connection 33 further includes a pivoted bell crank 45. The bell crank 45 is supported on a fixed pivot in adjacent relation to the valve 32. In the construction illustrated in the drawing a hanger 46 is secured to an adjacent frame member 47 of the stove and has a pivot pin 48 which supports the bell crank 45. The lower end of the link 40 is pivotally connected with an arm A of the bell crank 45. The connection between the link 40 and the bell crank arm A is preferably adjustable. In the case illustrated in the drawing a yoke 49 is adjustably threaded on the lower portion of the link 40 and is pivoted to the bell crank arm A to connect the link 40 with the bell crank 45. The bell crank 45 includes a second arm B which is in angular relation to the arm A. A link 50 connects the bell crank arm B with the lever 39 of the valve 32. The link 50 is preferably adjustably connected with the arm B and the valve lever 39. A clevis or yoke 51 is adjustably threaded on one end of the link 50 and pivotally connects the link with the arm B. A similar clevis or yoke 52 is adjustably threaded on the other end portion of the link 50 and pivotally connects the link with the outer end of the valve lever 39.

The above described linkage comprising the link 40, the bell crank 45 and the link 50 connects the cover 16 with the valve lever 39 so that raising of the cover 16 from its closed position to its open position swings the lever 39 to the position

illustrated in Figs. 1, 2 and 3 of the drawing where the valve 32 is open and movement of the cover 16 from the open position to the horizontal closed position illustrated in Fig. 4 of the drawing moves the valve lever 39 to the position where the valve 32 is closed. By adjusting the yoke 45 or by adjusting the yoke 51 or the yoke 52, or both of the latter yokes, the operative connection 33 may be made to close the valve 32 at any stage of downward movement of the cover 16. Thus the control or means 33 may be adjusted to effect closing of the valve 32 when the cover 16 is some distance from its horizontal position or when the cover 16 is adjacent and approaching its closed horizontal position.

It is believed that the operation of the stove control or stove construction provided by the invention will be readily understood from the foregoing detailed description. Under normal operating conditions the pilot burner 37 as well as the pilot burner (not shown) of the oven 11 may remain ignited at all times. Assuming that the cover 16 is in its open or vertical position illustrated in Figs. 1, 2 and 3 of the drawing the valve 32 is open so that gas is supplied to the valves 23 of the top burners 19. Accordingly, the top burners 19 may be selectively and individually put into use by the valves 23. The burner of the oven 11 may, of course, be controlled by the oven control valve 24 in the usual manner. When the top burners 19 are extinguished and no longer required the cover 16 may be swung to its closed substantially horizontal position illustrated in Fig. 4 of the drawing. This closing of the cover 16 operates to close the valve 32. It will be apparent that downward movement of the cover 16 is transmitted to the bell crank 45 by the link 40 causing turning of the bell crank and the link 58 in turn transmits movement from the bell crank to the lever 39 of the valve 32 so that the valve lever is moved to the position illustrated in Fig. 4 of the drawing when the cover is lowered to its closed position. Accordingly, the supply pipe 30 of the top burners 19 is closed or cut off from the main supply pipe 31 when the cover 16 is closed. In the event that one or more of the top burners 19 is left burning when the cover 16 is closed, as just described, closing of the valve 32 by the operative connection 33 cuts off the supply of gas to the burner 19 thus extinguishing the burner. In the event that one of the valves 23 is inadvertently opened or is opened by a child when the cover 16 is in its closed position the burner 19 governed by the said valve 23 is not ignited as the supply of gas is completely cut off from the header pipe 21 supplying the top burners 19.

When it is desired to use the top burners 19 of the stove the cover 16 is raised to its open or vertical position illustrated in Figs. 1, 2 and 3 of the drawing. Opening of the cover 16 is accompanied by opening of the valve 32. When the cover 16 is raised the link 40 moved by the cover 16 transmits movement to the bell crank 45 causing turning of the bell crank 45 and the link 58 is in turn moved by the bell crank to swing

the valve lever 39 to the position illustrated in Fig. 2 of the drawing where the valve 32 is open. Thus the header pipe 22 of the top burners 19 is automatically connected with the main supply pipe 31 when the cover is raised. It will be observed that the valve 32 does not control the pipe 25 and, therefore, opening and closing of the cover 16 does not in any way affect the pilot burner 27 or the burners of the oven 11.

The control means of the present invention assures the extinguishing of the burners 19 when the cover 16 is closed and definitely prevents igniting of the burners 19 when the cover is in the closed position, thereby preventing injury and destruction of the cover 16 by heat from the 16 burners 19 and avoiding the danger of escaping unburned gas from the top burners of the stove when the cover is closed. The control means of the invention is simple and inexpensive and may be readily embodied in typical ranges, and 20 cooking stove constructions.

Having described only a typical preferred form and application of our invention, we do not wish to be limited or restricted to the specific details herein set forth, but wish to reserve to ourselves 25 any variations or modifications that may appear to those skilled in the art or fall within the scope of the following claims.

Having described our invention, we claim:

1. In a stove, the combination of, a plurality 30 of burners, a fuel supply pipe, manually operable valves controlling the delivery of fuel from said pipe to the individual burners, a valve controlling said pipe and having a turnable control part, a cover for the burners movable between open and 35 closed positions relative to the burners, and an operative connection between the cover and the said valve operable to open the valve when the cover is moved to the open position and operable to close the valve when the cover is moved to the 40 closed position, said connection including a pivoted bell crank, a link pivotally connected with the cover and the bell crank and a link pivotally connected with the bell crank and the said control part of the valve whereby movement of the 45 cover causes turning of the valve control part.

2. A stove comprising, a body, spaced top burners on the body, a hinged cover on the body movable between a closed position where it covers the top burners and an open position where the 50 top burners are exposed for use, a fuel supply pipe, a header pipe in communication with the top burners, a pipe connecting the header pipe with the supply pipe, a valve in the last named pipe, and a positive operating lever connection 55 between the cover and said valve closing the valve when the cover is closed and opening the valve when the cover is raised, said connection including, a link connected with the cover, a pivoted bell crank, a connection between said link 60 and the bell crank, a link connected with the valve, and a connection between the last named link and the bell crank, at least one of the last named connections being adjustable.
